UNITED STATES PATENT OFFICE.

SAMUEL D. RUTH, OF BEATRICE, NEBRASKA.

PAPER AND ENVELOP FEEDING ATTACHMENT FOR TYPE-WRITERS.

No. 857,677.

Specification of Letters Patent.

Patented June 25, 1907.

Application filed December 29, 1905. Serial No. 293,803.

To all whom it may concern:

Be it known that I, SAMUEL D. RUTH, a citizen of the United States, residing at Beatrice, in the county of Gage and State of Nebraska, have invented a new and useful Paper and Envelop Feeding Attachment for Type-Writers, of which the following is a specification.

This invention relates to devices of that type employed for feeding envelopes, postal cards, or slips of paper to typewriting machines, and has for its principal object to provide a device of simple construction which may be readily attached to, or removed from an ordinary form of typewriting machine, and further to provide mechanism whereby the feeding means may be quickly thrown into and out of gear, in order to stop the feed when necessary.

20 A further object of the invention is to improve and simplify the construction of the feeding mechanism, and a still further object is to provide a novel form of holder that may be readily adjusted to contain envelopes, 25 cards, or slips of different length.

With these and other objects in view, as will more fully hereinafter appear, the invention consists in certain novel features of construction and arrangement of parts, herein 30 after fully described, illustrated in the accompanying drawings, and particularly pointed out in the appended claims, it being understood that various changes in the form, proportions, size and minor details of the structure may be made without departing from the spirit or sacrificing any of the advantages 35 of the invention.

In the accompanying drawings:—Figure 1 is a sectional plan view of an envelop feeding 40 attachment constructed in accordance with the invention. Fig. 2 is a vertical section of the same on the line 2—2 of Fig. 1. Fig. 3 is a rear elevation of the attachment showing the arrangement of the feeding rollers and 45 their gearing connections. Fig. 4 is an end view looking from the right of Fig. 3.

Similar numerals of reference are employed to indicate corresponding parts throughout the several figures of the drawings.

The present invention relates to feeding devices of that general type shown and described in Letters Patent of the United States granted to me on December 12, 1905, 55 No. 807,321, and is designed to be operated

from a gear on the shaft of the roller platen, as described in said Letters-Patent.

The casing 18 of the attachment is preferably rectangular in form, and is supported by a number of brackets 17, which are attached to the typewriter carriage.

The casing is preferably formed of metal, and is provided at its lower rear edge with a discharge slot 19, the width of which may be regulated by an adjustable false bottom 20, 65 sliding on the bottom member of the main casing, and provided at its rear edge with upturned lugs, to which are swiveled the inner ends of screws 21 that pass through openings formed in the front wall of the casing, and by 70 adjusting these screws, the width of the delivery slot may be accurately regulated in accordance with the thickness of the envelopes, postal cards, or slips of paper to be fed.

Arranged within the casing is a plate 22, 75 that is forced toward the rear by a compression spring 23, and the envelopes or other articles to be fed are placed between this plate and the rear wall of the casing, and are forced by the spring tightly against such rear wall. 80

The plate 22 and the front plate of the casing are provided with slots 25 for the passage of rods 26. These rods are provided with collars 27 that bear against the inner face of the front wall of the casing, and the outer 85 ends of the rods are threaded for the reception of milled or knurled nuts 28 which may be clamped tightly against the front of the casing for the purpose of firmly locking the rods 26 in any position to which they may be 90 adjusted. These rods are adjustable toward and from each other to accommodate envelopes, postal cards or slips of paper of different lengths, and in order to hold the articles from independent longitudinal play, so that all 95 may enter at the same point in the length of the roller platen.

At a point below the discharge slot 19 is a pair of rollers 29 and 30, having shafts 31 and 32, respectively, the shaft 31 having fixed 100 bearings in the frame or casing, while the shaft 32 is engaged by leaf springs 33 which tend to force the shaft 32 in the direction of the shaft 31, and thus keep the two rollers in intimate contact, so that positive feed of articles will be assured. These rollers are connected by intermeshing gears 34, although in some cases the gears will not be necessary.

Secured rigidly to the shaft 31 is a sprocket wheel 36, and pivoted to the shaft is a swing-

ing frame 37 which carries at its front end a shaft 38 to which is secured a sprocket wheel 39, and the sprocket wheel 36 is connected to the sprocket wheel 39 by a link belt 40. The shaft 38 further carries a gear or pinion 41, (Fig. 1) which may mesh with a gear on the shaft of the roller platen, the engagement of the pinion with the gear being controlled by the frame 37 which may be swung on shaft 31 for the purpose of engaging or disengaging the pinions and gear. In order to lock the pinion in its engaged or disengaged position, the outer end of the frame 37 is provided with a pivoted rod 42 that extends through a suitable opening formed in a boss 43 projecting from one side of the casing, and said boss has a threaded opening for the passage of a clamping screw 44 which may be forced into engagement with the rod for the purpose of locking said rod in any adjusted position. In this manner the pinion may be readily moved toward or from the gear of the roller platen, and may be quickly locked in operative or inoperative positions.

25 Projecting from the rear of the frame are two sets of ears 47—48, and these ears have bearing openings for the reception of shafts 49—50, respectively. The shafts carry discharging rollers 51 and 52 that may be formed of wood or of rubber, or of other suitable material, and preferably are provided with projecting pins 53 which positively engage with the envelopes or cards and force the same between the feed rollers 29 and 30. 30 The shaft 49 of the lower discharging roller is provided with a sprocket wheel 54, that is connected by a link belt 55 to a sprocket wheel 57 on the end of a shaft 31, so that the lower discharging roller may be positively driven at all times.

35 It is not in all cases essential to positively drive the upper roller 52, but in order to provide for such positive operation when necessary, the shaft 49 carries a loose sprocket wheel 58 that is connected by a link belt 59 to a sprocket wheel 60 on the shaft 50 of the upper roller. The lower sprocket wheel 58 may be locked to the shaft 49 by a clutch 62, that is under the control of an operating lever 63, fulcrumed on a lug 64 at one side of the frame, and the construction is such that the clutch may be readily moved to locking or release position as may be required by the character and size of the articles to be fed.

40 45 50 55 If the device is used for addressing purposes the movement of the roller platen necessary for the placing of the name and address on different lines of one envelop will operate the several feed rollers, and the second envelop will be drawn out to a position corresponding to the extent of movement of the platen, and in withdrawing the addressed en-

velop, the platen will be operated, and the second of the envelops will be fed to feeding position. In order to prevent contact of the envelop, or paper, with the bottom of the casing, when said envelop or paper is discharged from the front of the roller platen, deflecting guides are secured to the lower front portion of the casing, and are extended rearward to a point adjacent to the front of the roller platen.

I claim:—

1. In a feeding attachment for typewriting machines, a casing, feed rollers for discharging articles therefrom, a gear on the shaft of one of the feed rollers, an adjustable frame pivotally mounted on the shaft and arranged to swing in a vertical plane, a short shaft at the free end of said frame, a driven gear carried by said short shaft, and a sprocket wheel and link belt connection between the short shaft and the feed roller shaft, whereby movement may be imparted to said feed rollers.

2. In a device of the class described, the combination with a casing having a discharge opening, feed rollers pivoted adjacent to said opening, a shaft carrying one of said feed rollers, a sprocket wheel on said shaft, a frame pivoted to the shaft and provided at its free end with a short shaft, a sprocket wheel and a gear wheel carried by the short shaft, a link belt connecting the two sprocket wheels, a rod pivoted to the free end of the frame, a lug carried by the casing and having an opening for the passage of the rod to permit adjustment of the gear wheel into and out of operative position, and means for locking said rod to hold the frame in any adjusted position.

3. In a device of the class specified, the combination with a casing having a discharge slot, of feed rollers adjacent to the slot, shafts carrying said feed rollers, means for revolving one of said shafts, a pair of discharge rollers arranged at the rear of the casing and projecting through openings formed in the wall thereof, shafts carrying the discharging rollers, a link belt connection between the driven feed roller and the lower discharging roller, a loose sprocket wheel carried by the shaft of the lower discharging roller, and clutching means for engaging and disengaging said shaft and sprocket wheel, a sprocket wheel on the shaft of the upper discharging roller, and a link belt connecting said sprocket wheels.

In testimony that I claim the foregoing as my own, I have hereto affixed my signature in the presence of two witnesses.

SAMUEL D. RUTH.
